CLAIM

The ornamental design for a phone case, as shown and described.

DESCRIPTION

FIG. 1 is a front, top, and right-side perspective view of a phone case showing my new design;

FIG. 2 is a rear, left-side, and bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of a portion indicated with numeric 9 in FIG. 2; and,

FIG. 10 is an enlarged view of a portion indicated with numeric 10 in FIG. 2.

The dot-dash broken lines in FIGS. 2, 9, and 10 form no part of the claimed design and delineate portions of the claimed design that are shown on an enlarged scale in FIGS. 9 and 10.
